UNITED STATES PATENT OFFICE

WILLIAM ANDERSON, OF CHICAGO, ILLINOIS

FILING MACHINE

Application filed July 5, 1928. Serial No. 290,653.

The invention relates to a novel machine for filing metals and other hard materials.

Its primary object is the provision of a power-driven appliance by means of which 5 the filing of metals and like hard substances may be accomplished mechanically as distinguished from the manual filing commonly done.

A further object of the invention is the 10 production of a machine of the character mentioned, the organization of which is such as to insure accuracy in the filing operation, so that the completed work shall present a 15 nicety of finish comparable to the finish resulting when filing is done by hand.

Furthermore, the invention also has in contemplation a filing machine which may operate on the work both externally and internally thereof. The machine, therefore, is 20 capable of general application within the sphere for which it is designed, and is so constructed as to enable the user of the same quickly to adapt the machine for operation on either the exterior or the interior faces 25 of the material presented to the machine.

Other objects and advantages of the invention will become apparent as the nature of the improvements is better understood, the invention consisting substantially in the novel 30 construction, combination and arrangement of parts hereinafter fully described, illustrated in the accompanying drawings, and finally pointed out in the appended claims.

The form of the machine which is disclosed 35 herein is a practical adaptation of the invention, but the latter is capable of embodiment in other forms. The present delineation, therefore, is not to impose restriction on the invention, but is to illustrate the incorporation 40 of the inventive concept in such shape as will demonstrate the practicability of the invention for the purposes for which it is intended.

In the drawings—

45 Fig. 1 is a side elevation of a filing machine constructed in accordance with the invention.

Fig. 2 is a medial section thereof taken on the line 2—2, Fig. 1.

50 Fig. 3 is a detail sectional view, on an enlarged scale, illustrating the filing elements

in their relation to the supporting guides thereof, the section being taken on the line 3—3, Fig. 2.

Fig. 4 is a detail sectional plan view on the line 4—4, Fig. 3. 55

Fig. 5 is a similar view on the line 5—5, Fig. 3.

Fig. 6 is a detail elevation of the adjustable mounting of the work table, the latter being shown in section. 60

Fig. 7 is a fragmentary elevation of the chain of filing elements.

Fig. 8 is a face elevation of an abrasive element designed for substitution for the filing elements. 65

Fig. 9 is an edge elevation thereof.

Fig. 10 is a transverse sectional view on the line 10—10, Fig. 9.

Fig. 11 is a face elevation of a buffing element. 70

Fig. 12 is an edge elevation thereof.

Fig. 13 is a transverse sectional view on the line 13—13, Fig. 12.

Referring now in detail to the accompanying drawings, the numeral 10 designates the 75 frame of the machine. It is in the form of a supporting pedestal, the body thereof being curved and terminating at its lower end in a supporting base 11 by which the frame is sustained in applied position to a floor or 80 other surface. The base 11 is provided with a bearing sleeve 12 which receives a driving shaft 13. At one end of said shaft a driving pulley 14 is suitably secured thereto over which a belt 15 is trained, and by which power 85 is applied to the shaft 13 from any suitable source. At the opposite end of the shaft 13 there is mounted for rotation with the shaft a driving band wheel 16, the face of which is relatively wide. 90

At the top of the frame 10 a pair of spaced guide rods 17 is located. A sliding cross-head 18 is adjustably mounted on said guide rods 17, the movement of said crosshead being controlled by an adjusting screw 19, which screw is threaded into the top portion of the frame 10. This screw is provided with a hand wheel 20 at its lower end for rotating the screw. The upper end of the screw 19 contacts the lower side of the crosshead 18, so 100

that on rotation of the screw in one direction the crosshead will be moved upwardly, and on the reverse rotation of the screw the crosshead will move downwardly.

Hingedly connected with the crosshead 18, 5 as by a suitable pintle 21, is a supporting head 22, which, by reason of the hinged connection with the crosshead 18, is capable of rocking movement in relation to the crosshead. The supporting head 22 carries a stub axle 23, said 10 stub axle being fixedly connected to the head 22, and mounted for free rotation on said axle 23 is an idler band wheel 24, having a relatively wide face, and corresponding in dimension to the driving band wheel 16. The 15 wheel 24 is held for rotation on the axle 23 by a securing nut 25.

Extending rearwardly from the cross head 18 is a supporting arm 26 in which is positioned a tensioning bolt 27, the upper end 20 of said bolt 27 passing through the rear end of the supporting head 22. The threaded end of the bolt 27 receives a winged nut 28, and said nut bears against the head 22 for 25 adjustment purposes. Interposed between the supporting arm 26 and the rear end of the head 22 is a tensioning coil spring 29, the ends of which are received by cupped washers 30 which bear against the arm 26 and the head 22, the expansive force of said spring 30 serving to urge the rear end of the supporting head 22 away from the supporting arm 26 against the pressure exerted by the winged nut 28 in its various positions of adjustment.

35 By adjustment of the tensioning spring 29 under the action of the bolt 27 and its winged nut 28 the relation of the idler band wheel 24 to the driving band wheel 16 is controlled. This control is primarily for the purpose of 40 properly tensioning a flexible belt 31, preferably in the form of an endless steel band or ribbon, which is trained over the wheels 16 and 24. The belt 31 serves as a carrier for a plurality of filing elements 32. By referring 45 to Fig. 7 it will be observed that the ends of the band 31 are provided with interfitting perforated ears 33 which receive a connecting pin 34, whereby the ends of the band 31 are secured together. By removal of the pin 50 34 the ends of the band 31 readily may be separated, the purpose of which presently will appear.

Each of the filing elements 32 constitutes 55 an individual file. They are constructed as files usually are constructed, and their outer faces are scored to provide the necessary teeth requisite for filing purposes. As seen in Fig. 1, the elements are in vertical alignment when positioned at the vertical 60 stretches of the belt 31.

As the elements pass around the wheels 16 and 24 they break joint, in order to permit 65 traverse of the belt about these wheels, and after leaving the wheels the elements again become aligned. To permit this flexing of

the belt, and the breaking of the joints between the several filing elements, each of the latter is attached to the belt independently of the other elements. That attachment is effected by means of a single screw 35 which 70 passes through a perforation at a point midway the ends of each of the filing elements.

The head of the screw 35 is countersunk in the exposed face of the filing element so as not to project therefrom. Each of the 75 screws 35 is threaded into an anchoring button 36 which is swaged into fixed relation with the belt 31, the buttons being suitably spaced apart so as to hold the filing elements in substantial abutting relation with each 80 other when they are in alignment on said belt. These buttons 36 also are countersunk into the inner faces of the filing elements, so that said inner faces lie flat against the belt 31.

85 That the filing elements 32 may be held against lateral rocking movement on the belt 31 they are also provided with perforations 37, one of which is placed at each side 90 of the attaching screws 35. These perforations receive guide studs 38 which are swaged into fixed relation with the belt 31 and located one at each side of each of the attaching screws. The exposed ends of the studs 38 are rounded, and readily enter and fit the 95 perforations 37. By reason of the construction described, it is evident that each of the filing elements 32 cannot swivel upon the attaching screws 35 and the anchoring buttons 36, and thereby are prevented swerving from 100 parallel relationship with the belt 31. They are always held in proper alignment with the belt to be guided accurately by the latter against the surface of the material which is 105 under treatment.

To support the work in proper relation to the filing elements 32 for action of the latter thereon a table 39 is adjustably mounted on a supporting arm 40 which forms part of the base 11 of the machine. This arm 40 110 is bifurcated, as clearly appears in Fig. 5, which bifurcation receives a depending flange 41 carried at the lower side of the table 39. The flange 41 has an arcuate slot 42, and passing through said slot is a fixed guide 115 pin 43 and an adjusting bolt 44, said pin and said bolt being mounted in the supporting arm 40. By reason of the arcuate formation of the slot 42, and the reception thereby of the pin 43 and the bolt 44, the work table 39 may be properly adjusted to the plane of movement of the filing elements 32, thereby insuring proper presentation of the filing action of said elements 32. When adjusted to the desired position the bolt 44 is tightened, 120 and the work table thereby is held in its position of adjustment.

The table 39 has an opening 45 through which the band 31 and the filing elements 32 125 pass in the travel of the elements.

For supporting the filing elements in rigid relation to the work on the table 39, and to maintain rigidity of each of these elements as it crosses the face of the work, a plurality 5 of guides is employed. The construction of these guides is illustrated in detail in Figs. 3, 4 and 5. They are so disposed with respect to the work table 39 as to position a pair of guides above the table, and another 10 pair thereof below the table. Furthermore, the disposition of the guides at both the upper and under sides of the table is such as to afford a guide at the front of the filing elements and also one at the rear. The upper 15 and the lower rear guides are likewise so related that each filing element will overlap these rear guides in the passage of the element across the face of the work, and thereby hold the filing element which is in action 20 on the work rigidly with respect to the latter, and thus afford a steady cutting action of that filing element. In the attainment of the arrangement just mentioned the forward end of the top of the 25 frame 10 is provided with a guide head 46 having a bore 47 of polygonal cross-section, preferably being hexagonal. This bore receives a vertically-adjustable supporting 30 spindle 48 which corresponds in contour to the contour of the bore 47. The spindle 48 is held in different positions of adjustment in the guide head 46 by a set screw 49 the inner end of which impinges against the spindle 48.

35 The spindle 48 sustains a pair of divergent supporting arms 50 and 51, which arms are adjustably mounted in relation to the spindle 48 by set screws 52, one of which is carried by each of these arms and cooperating 40 with the spindle 48 to hold the supporting arms 50 and 51 at different positions along the spindle, as occasion may require such adjustment. The arm 50 carries the front upper guide and the arm 51 the rear upper 45 guide. Connected to these respective supporting arms are adjustable supporting blocks 53 and 54, respectively, each of said blocks being held on its supporting arm by a set screw 55.

50 The front upper guide comprises a body member 56 at the opposite sides of which are positioned flange members 57, suitably secured to the body member 56, as by screws 58. The flange members 57 are perforated 55 and receive the trunnions of a series of contact rollers 59, the diameters of which are sufficiently great for the peripheral portions of the rollers to project beyond the edges of the flange members for engagement by the 60 filing elements 32, and thereby provide rolling contacts for these elements as they are guided to the work on the table 39. The front upper guide also includes a vertically-extending attaching shank 60 which is received by a perforation 61 in the supporting

block 53, in which block the shank 60 is adjustably held by a set screw 62.

The rear upper guide comprises a body member 63, and at opposite sides of this member are positioned flange members 64, riveted or otherwise suitably secured to the body member 63, as at 65. The free edges of these flange members are turned inwardly to constitute guide ribs 66, said ribs being received by oppositely disposed vertical 70 grooves 67 formed at opposite sides of a vertically-adjustable shoe 68. By the engagement of the guide ribs 66 with the grooves 67 the shoe 68 is capable of vertical sliding movement with respect to the body 75 member 63 of the upper rear guide. This shoe 68 is held in adjusted position along the body member 63 by a set screw 69 carried by said body member and adapted to impinge against the shoe. The purpose of 80 this adjustment is to enable the shoe 68 to be raised and lowered with reference to the table 39 so that, regardless of the thickness of the work positioned on the table 39 for the filing action of the elements 32, the shoe 85 may be properly adjusted to accommodate the position of the lower end thereof in relation to the work to rigidly support the filing elements 32 as they pass across the 90 face of the work.

95 The shoe 68 has a series of concave bearings 70 at spaced intervals throughout its length, said bearings receiving a series of contact rollers 71, said rollers being provided with flanged heads 72 so as to be held against 100 lengthwise displacement from the bearings 70. The contact rollers 71 are also held in the bearings 70 by a keeper plate 73. The length of this plate is coextensive with the shoe 68, and said plate 73 is provided with a series of transverse slots 74, the edges of 105 which are curved in conformity with the curvature of the rollers 71 so as to permit free rotation of the rollers in the slots. The thickness of the plate 73 is less than the diameter of the rollers 71 so that segments of the rollers project through the slots 74 for contact by the carrier belt 31, and thereby provide a rolling contact for this belt as it 110 passes over the upper rear guide.

115 The body member 63 has an upwardly-extending attaching shank 75, and said shank is received by a perforation 76 formed in the supporting block 54 and adjustably held therein at different points by a set screw 77. This set screw permits the bodily 120 extent of the adjustment of the upper rear guide, while the set screw 69 permits the vertical adjustment of the shoe 68 independently of the adjustment of the upper rear guide. Thus, after the bodily adjustment of the upper rear guide to the desired position, it is still possible to adjust the shoe 68 towards or away from the table 39, thereby 125 enabling the lower end of the shoe to be 130

properly positioned with respect to the work independently of adjustment of the guide. This is of considerable importance in order to give rigidity of support to the filing elements 32 as they pass over the face of the work. The carrier band 31 being flexible, it is obvious that pressure of the work against the filing elements 32, if the band be unsupported from the rear, will have a tendency to flex the band in a rearward direction, and thus interfere with the proper filing action of these elements. With the shoe 68 lowered to the desired point so as to afford a rigid backing for the band 31, it is evident that the band 31 will not yield under pressure of the work, and the filing elements 32 will be held up to the work for proper filing of the same.

The lower rear guide is generally similar in construction to that of the upper rear guide in that it includes a body member 78 having at its front face, and at spaced intervals throughout the length thereof, a series of concave bearings 79. These bearings receive a series of contact rollers 80 which are provided with flanged heads 81 to prevent lengthwise displacement of the rollers from the bearings 79. The rollers 80 are also held from displacement from the bearings 79 by a keeper plate 82 the length of which is coextensive with that of the body member 78. The plate 82 is provided with a series of transverse slots 83, the edges of these slots being curved in conformity with the curvature of the rollers 80 to permit free rotation of the rollers in the slots. The thickness of the plate 82 is less than the diameter of the rollers 80, so that segments of these rollers project through the slots 83, similar to the rollers 71, for contact by the carrier belt 31. This provides a rolling contact for said belt 31 as it passes over the lower rear guide.

The keeper plates 73 and 82 are detachably held on the shoe 68 and the body member 78, respectively, by screws 84, or their equivalent. This permits ready displacement of the keeper plates, and removal of the rollers 71 and 80 or replacement thereof should such be necessary.

The lower rear guide is carried by an L-shaped supporting bracket 85. This bracket is mounted on one face of the supporting arm 40, being held in position thereon by a pair of screws 86 received by a pair of elongated slots 87 formed in the body of the bracket 85, the screws being threaded into said supporting arm 40. The provision of the slots 87 enables adjustment of the bracket 85 in the lengthwise direction thereof, and this permits the lower rear guide to be adjusted towards or away from the carrier belt 31 and the filing elements 32 mounted thereon. The immediate connection of the body member 78 of the lower rear guide is through a pair of screws 88 which engage said body member 78 and

are received by a pair of slots 89 formed in the foot portion of the supporting bracket 85. The screws 88 and slots 89 permit adjustment of the lower rear guide crosswise of the belt 31, and insure proper positioning of the guide so that the flanged heads 81 of the rollers 80 may embrace the side edges of said band.

The lower front guide partakes generally of the construction of the upper front guide. It includes a body member 90 at the opposite sides of which are positioned flange members 91. These are suitably secured to the body member 90, as by screws 92. The members 91 are perforated and receive the trunnions of a series of contact rollers 93. The diameters of these rollers are sufficiently great for the peripheral portions thereof to project beyond the edges of the flange members 91 for engagement by the filing elements 32, thus providing rolling contacts for these elements as they are guided away from the work in passing downwardly through the opening 45 of the table 39. The lower front guide is carried by an L-shaped supporting bracket 94. This bracket 94 is mounted on the supporting bracket 85 by a pair of bolts 95, said bolts being received by the slots 87. The bolts 95 and the slots 87 permit adjustment of the supporting bracket 94 towards and away from the carrier belt 31 and the filing elements 32 thereon, thus adapting the lower front guide for proper presentation to the filing elements to guide the same as they pass from the work. The immediate connection of the lower front guide with the L-shaped bracket 94 is effected by a pair of bolts 96. These bolts are threaded into the body member 90 of said guide and are received by a pair of vertically-elongated slots 97 formed in the foot of the bracket 94. These bolts and slots permit slight vertical adjustment of the lower front guide towards and away from the table 39.

The foregoing description has in contemplation the use of the elements 32 as files, thus effecting by mechanical power that which generally is done by hand. It is clearly within the purview of the invention to substitute for the filing elements 32 other instrumentalities designed for abrasive and buffing purposes. In Figs. 8 to 13 inclusive are illustrated such instrumentalities.

As instancing the use of an abrasive element, the invention has in view that construction illustrated in Figs. 8, 9, and 10. This includes a shoe 98 having an attaching rib 99 formed at one face thereof provided with under-cut edges 100. About this attaching rib 99 a body of abrasive grits 101 is molded. Preferably, these grits are carborundum or the like. The abrasive grits, therefore, may be utilized for abrasive purposes, as distinguished from filing.

As instancing the use of a buffing element, the invention may employ that construction illustrated in Figs. 11, 12 and 13. This in-

cludes a metallic shoe 102. Suitably connected thereto is a hardened fiber facing 103, and cemented to said facing 103, or otherwise suitably connected thereto, is a layer of felt 5 104, or other suitable material of a yielding nature, and of such character as to permit a facing of emery grits 105, or other suitable material, to be applied thereto, as by cementing. As distinguished from the abrasive grits 10 10, illustrated and described in connection with the element shown in Figs. 8, 9 and 10, which is designed for heavy, coarse abrasive cutting, the emery grits of the element shown in Figs. 11, 12 and 13 will afford a finer cutting, thereby 15 enabling the element to be employed for buffing or polishing purposes.

The machine herein shown and described is particularly adapted for the filing and other treatment of die work. In this work 20 it is essential for the filing to be done at the interior as well as the exterior of the work. When required for interior filing, it will be understood that the tensioning action of the idler band wheel 24 is released by proper 25 manipulation of the bolt 27 and its controlling wing nut 28. This flexes the carrier belt 31 sufficiently to permit the ends thereof to be disconnected by the removal of the pin 34 from the interfitting ears 33. With the ends 30 thus separated one of the same is threaded through the opening of the work, thus positioning the carrier belt and the filing elements at the interior of the work. The ends of the carrier belt are then connected and the 35 belt again placed under tension by proper adjustment of the idler band wheel 24 in relation to the driving band wheel 16. As the thickness or height of the work on the table 39 will vary from time to time, it 40 is necessary to adjust the upper guides so as properly to position the same with respect to the work, and thus to insure rigidity of the filing elements as they pass across the face of the work. The primary adjustment 45 in this respect is effected by releasing the set screws 62 and 77 and moving the attaching shanks 60 and 75 of the guides vertically in the supporting blocks 53 and 54 to the required positions. After tightening the set 50 screws 62 and 77 the shoe 68 is then adjusted towards the table 39 so as to lower it as near as possible to the table and position the lower end thereof in such proximity to the work, or to the table, as will insure a rigid backing or 55 support for the carrier belt 31 and the filing elements 32 as the latter pass across the face of the work. If the work is not positioned immediately in the downward path of movement of the shoe 68, the latter may be lowered 60 into the opening 45 and into contact with the upper end of the lower rear guide. In that event a dowel stud 106 will enter a recess or socket 107 formed in the lower end of the shoe 68, and thereby effect a rigid relation 65 between the meeting ends of the upper and

lower rear guides. The machine now being set in operation, the filing elements 32 pass rapidly across the face of the work, cutting away the face in the characteristic manner of the action of files. When the work is 70 completed, detachment of the ends of the carrier belt 31 will permit the die to be removed from the carrier belt and the work table.

When the filing operation is being performed on the exterior of the die or other work presented to the filing elements, the shoe 68 is positioned with respect to the work and the table 39 in a manner which is obvious from the above description. This positioning of the shoe 68 establishes the proper rigid support for the filing elements, and in pressing the work against the filing elements the belt 31 is prevented flexing and the filing elements are held rigidly to the work. 75 80 85

In the positioning of the shoe 68, it will be understood that it is moved to such a point towards the table 39 that with the lower end of each filing element 32 positioned between the lower front and rear guides the upper end 90 of said element will overlap and be supported by the shoe 68. In that position of the filing element the greatest resistance is offered thereby to the pressure of the work as the latter is presented to the filing element for 95 action by the latter on the work. The filing element, therefore, is braced at its upper and lower ends, and its accurate cutting action thereby assured.

In the traverse of the carrier belt 31 and the filing elements 32 over the rollers 71 and 80, of the upper and lower rear guides, the flanged heads 72 and 81 of these rollers embrace the carrier belt and the filing elements, and thus prevent crosswise movement or 100 swerving of the same in relation to the work under treatment. These flanged heads thus effectually guide the carrier belt in its travel. 105

I claim:

1. In a machine of the class described, the 110 combination with a driving wheel and a driven wheel, of a flexible carrier supported by said wheels, a series of treating elements mounted on said carrier and each affixed thereto at a point midway its ends, whereby 115 to permit flexing of the carrier in its travel about said wheels and to adapt said elements to break joint with each other as they pass over the wheels, aligning means at opposite sides of the point of attachment of each treating element with the carrier, said aligning means serving to connect each treating element with the carrier to hold the same marginally aligned with the marginal portions of the carrier, a work support adjacent to 120 the path of movement of said carrier for sustaining the work in its presentation to the treating elements, and means for guiding the treating elements in their movement relatively to the work. 125 130

2. In a machine of the class described, the combination with a driving wheel and a driven wheel, of a flexible carrier supported by said wheels, a series of treating elements mounted on said carrier to permit flexing of the carrier in its travel about said wheels, a work support adjacent to the path of movement of said carrier for sustaining the work in its presentation to the treating elements, means for rigidly supporting each of said treating elements in its passage across the face of the work against pressure of the latter in its presentation to the treating element, said supporting means including guiding means for embracing the edges of the carrier and treating elements to maintain the same for proper presentation to the work.

3. In a machine of the class described, the combination with a driving wheel and a driven wheel, of a flexible carrier supported by said wheels, a series of treating elements mounted on said carrier to permit flexing of the carrier in its travel about said wheels, a work support adjacent to the path of movement of said carrier for sustaining the work in its presentation to the treating elements, means for rigidly supporting each of said treating elements in its passage across the face of the work against pressure of the latter in its presentation to the treating element, said supporting means including guiding means for embracing the edges of the carrier and treating elements to maintain the same for proper presentation to the work, and means for affording relative adjustment of the guiding means with respect to the work support to vary the supporting relation of the guiding means to the passage of the treating elements across the face of the work.

4. In a machine of the class described, the combination with a driving wheel and a driven wheel, of a flexible carrier supported by said wheels, a series of treating elements mounted on said carrier and each affixed thereto at a point midway its ends, whereby to permit flexing of the carrier in its travel about said wheels and to adapt said elements to break joint with each other as they pass over the wheels, means for maintaining said elements marginally aligned with the marginal portions of the carrier, a work support adjacent to the path of movement of said carrier for sustaining the work in its presentation to the treating elements, means for rigidly supporting each of said treating elements in its passage across the face of the work against pressure of the latter in its presentation to the treating element, and guiding means included in said supporting means for embracing the edges of the carrier and treating elements to maintain the same for proper presentation to the work.

5. In a machine of the class described, the combination with an endless carrier, of a series of treating elements mounted thereon, a

work support adjacent to the path of movement of said carrier for sustaining the work in its presentation to the treating elements, supporting guides arranged above and below said work support and between which said treating elements are adapted to be passed in their movement to and from the work to guide the treating elements in their movement relatively to the work, the guides of the upper pair being aligned with the guides of the lower pair for rigidly supporting each of said treating elements in its passage across the face of the work against pressure of the latter in its presentation to the treating element, means for effecting relative adjustment between the guides of each pair of said supports, and means for effecting relative adjustment of each of said pairs of guides with respect to the other pair.

6. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, each of said pairs of guides including a front and a rear guide spaced apart to permit passage therebetween of said treating elements in their movement to and from the work to guide the treating elements in their movement relatively to the work, and an adjustable supporting shoe associated with the upper pair of said guides and movable towards and away from said work support.

7. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, each of said pairs of guides including a front and a rear guide spaced apart to permit passage therebetween of said treating elements in their movement to and from the work to guide the treating elements in their movement relatively to the work, and a plurality of contact rollers arranged at the inner faces of the guides of each pair to provide rolling contacts for said carrier and the treating elements in their passage through said guides.

8. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, each of said pairs of guides including a front and a rear guide spaced apart to permit passage therebetween of said treating elements in their

- movement to and from the work to guide the treating elements in their movement relatively to the work, an adjustable supporting shoe associated with the rear guide of the upper pair and movable towards and away from said work support, a plurality of contact rollers arranged at the inner face of the front guide of the upper pair and also at the inner face of said adjustable supporting shoe, and additional contact rollers arranged at the inner faces of the front and rear guides of the lower pair, said rollers providing rolling contacts for said carrier and the treating elements in their passage through said guides. 5 70
9. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, each of said pairs of guides including a front and a rear guide spaced apart to permit passage therebetween of said treating elements in their movement to and from the work to guide the treating elements in their movement relatively to the work, and a plurality of contact rollers arranged at the opposing faces of the guides of each pair to provide rolling contacts for said carrier and the treating elements in their passage through said guides, one of the guides of the upper and the lower pair having its rollers provided with flanged heads adapted to embrace the carrier and the treating elements, whereby to prevent crosswise movement of the same in relation to the work. 10 75
11. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, each of said pairs of guides including a front and a rear guide spaced apart to permit passage therebetween of said treating elements in their movement relatively to the work, and a plurality of contact rollers arranged at the opposing faces of the guides of each pair to provide rolling contacts for said carrier and the treating elements in their passage through said guides, the rollers of the rear guides of the upper and the lower pair being provided with flanged heads adapted to embrace the carrier and the treating elements, whereby to prevent crosswise movement of the same in relation to the work. 15 80
12. In a machine of the class described, the combination with a driving wheel and a driven wheel, of a flexible carrier supported by said wheels, a series of treating elements mounted at one face of the carrier and connected thereto to permit flexing of the carrier in its travel about said wheels, said treating elements being adapted to break joint with each other as they pass over the wheels, a work support adjacent to the path of movement of said carrier for sustaining the work in its presentation to the treating elements, and means arranged at opposite faces of said carrier for guiding the treating elements in their movement relatively to the work, said means embracing the treating elements and rigidly supporting the same against the pressure exerted by the work when the latter is fed to the treating elements. 20 85
13. In a machine of the class described, the combination with an endless carrier, and a series of treating elements mounted at one face thereof, of a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 25 90
14. In a machine of the class described, the combination with an endless carrier, and a 30 95
15. In a machine of the class described, the combination with an endless carrier, of a series of treating elements mounted thereon, a work support adjacent to the path of movement of said carrier for sustaining the work in its presentation to the treating elements, 35 100
16. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 40 105
17. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 45 110
18. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 50 115
19. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 55 120
20. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 60 125
21. In a machine of the class described, the combination with an endless carrier, of a series of treating elements mounted thereon, a work support adjacent to the path of movement of said carrier for sustaining the work in its presentation to the treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, and means for effecting relative adjustment of each pair of guides with respect to the other. 65 130

- series of treating elements mounted at one face thereof, of a work support adjacent to the path of movement of said carrier for sustaining the work in its presentation to the 5 treating elements, supporting guides arranged in pairs above and below said work support, the guides of each pair being disposed at opposite faces of said carrier for guiding the treating elements in their movement relatively to the work, said guides embracing the treating elements and rigidly supporting the same against the pressure exerted by the work when the latter is fed to the treating elements, means for effecting 10 relative adjustment of the guides of each pair of said supports, and means for effecting relative adjustment of each pair of guides with respect to the other.
15. In a machine of the class described, the combination with an endless carrier, and a series of treating elements mounted at one face thereof, of a work support adjacent to the path of movement of said carrier for sustaining the work in its presentation to 20 the treating elements, supporting guides arranged in pairs above and below said work support, one of the guides of each pair being disposed at the front of the carrier and the other at the rear thereof for guiding the 25 treating elements in their movement relatively to the work, said guides embracing the treating elements and rigidly supporting the same against the pressure exerted by the work when the latter is fed to the treating 30 elements, and means for effecting relative adjustment between the guides of each pair of said supports.
35. In a machine of the class described, the combination with an endless carrier, and a series of treating elements mounted at one face thereof, of a work support adjacent to the path of movement of said carrier for sustaining the work in its presentation to the treating elements, supporting guides arranged in pairs above and below said work support, one of the guides of each pair being disposed at the front of the carrier and the other at the rear thereof for guiding the 40 treating elements in their movement relatively to the work, said guides embracing the treating elements and rigidly supporting the same against the pressure exerted by the work when the latter is fed to the treating elements, and means for effecting relative 45 adjustment of each pair of said guides with respect to the other pair.
45. In a device of the character described, an open-sided frame, a driven wheel and a driving wheel mounted in spaced relation on said frame, a movable carrier mounted on said wheels and extending across the open portion of said frame, a series of treating elements mounted at one face of said carrier, a work support mounted on said frame in the path of travel of said carrier, a member ad-

justably mounted on the upper portion of said frame, a rigidly held roller for bracing said carrier against work forced against said treating elements, and a roller secured to said member and contacting said treating elements on the side opposite said bracing roller. 70

18. In a device of the character described, an open-sided frame, a driven wheel and a driving wheel mounted in spaced relation on said frame, a movable carrier mounted on said wheels and extending across the open portion of said frame, a series of treating elements mounted at one face of said carrier, a work support mounted on said frame adjacent the lower extension thereof and in the path of travel of said carrier, bracing and guiding means mounted on the upper portion of said frame, and adjustable means including a roller mounted on the upper portion of said frame, said roller contacting the operative side of said treating elements. 75

19. In a device of the character described, an open-sided frame, a movable carrier having a path of travel adjacent the open portion of said frame, a series of treating elements on one face of said carrier, a work support mounted on said frame in the path of travel of said carrier, a member adjustably mounted on the upper portion of said frame, means carried by said member for rigidly bracing and guiding said carrier, and a second means mounted on the lower portion of said frame and below said work support for rigidly bracing and guiding said carrier, said first named bracing and guiding means and 90 said second named bracing and guiding means being separated by a distance less than the distance between the terminal ends of each of said treating elements. 95

In testimony whereof I have hereunto subscribed my name.

WILLIAM ANDERSON.
